CLAIM

The ornamental design for a facial cleansing brush handle, as shown and described.

DESCRIPTION

FIG. 1 is a perspective view of a facial cleansing brush handle, showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines which cross over the full line showing are directed to environment, while all other broken lines in the drawings depict portions of the facial cleansing brush handle that form no part of the claimed design.

1 Claim, 7 Drawing Sheets
